REAR LOADING SCREW-FEED MECHANICAL PENCIL

Hans A. Bauer, Prairie View, Ill., assignor to
Autopoint Company, Chicago, Ill., a corpora-
tion of Illinois

Application November 13, 1945, Serial No. 628,174

8 Claims. (Cl. 120—18)

1

The present invention relates to mechanical pencils and especially to a novel construction of rear loading pencil.

Among the objects of the present invention is to provide a novel construction of rear loading mechanical pencil in which the barrel is provided with a non-removable tip but in which the tip is rotated or turned to advance or retract the lead.

A further object of the present invention is to provide a novel construction of feed key which may be quickly advanced or retracted by rotation of the tip in the proper direction, and when retracted, is so constructed, arranged and assembled as to facilitate loading from the rear of the pencil.

Another object of the present invention is the provision of a novel lead feeding mechanism for mechanical pencils so constructed and arranged as to feed several standard lengths of lead and thereby requiring less frequent loading of lead into the lead passage.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts illustrated in the accompanying drawings, and while there is shown therein a preferred embodiment, it is to be understood that the same is susceptible of modification and change, and comprehends other details, arrangements of parts, features and constructions without departing from the spirit of the invention.

In the drawings:

Figure 1 is a view in vertical cross-section through the body of the pencil, but with the cap shown partly in side elevation.

Figure 2 is an enlarged fragmentary view in vertical cross-section showing the assembly of the feed key and its associated parts.

Figure 3 is a view in cross-section taken in a plane represented by the line 3—3 of Figure 2.

Figure 4 is a view in perspective of the novel feed key.

Figure 5 is a view in vertical cross-section taken in a plane represented by the line 5—5 of Figure 1.

Figure 6 is a view similar to Figure 5 but showing the tilted position of the upper end of the key when it reaches the end of its upward travel, to uncover the lead passage and permit the insertion of a new supply of lead.

Fig. 7 is an enlarged, fragmentary perspective view of a portion of the barrel, tube, sleeve and feed key, parts thereof being broken away to more clearly show the relation of the parts and

2

the tube being withdrawn slightly from the base of the lead chamber or magazine.

Fig. 8 is a fragmentary view in perspective of the tube and showing the offset for receiving the feed key.

Fig. 9 is an enlarged view in vertical cross-section taken in a plane represented by the line 9—9 of Fig. 1.

Fig. 10 is a fragmentary perspective view of the upper end of the assembly shown in Fig. 7 but with the feed key retracted to its uppermost position.

Fig. 11 and 12 are cross-sectional views taken in planes represented by the lines 11—11 and 12—12, respectively, of Fig. 8.

Referring more particularly to the drawings and the novel embodiment therein selected to illustrate the invention, the pencil 1 comprises a barrel 2 having its lower end reduced at 3 to receive the tapered or conical part 4 of a tip assembly 5. This tip assembly is locked or anchored to the barrel by means of a locking ring, collar or the like 6 and an adjacent sleeve 6^a, whereby the tip is not removable but is rotatable to permit turning or rotation thereof to advance or retract the lead. As clearly shown in Figure 1, the tip assembly 5 consists of the conical part 4 which is preferably formed of a suitable plastic composition or the like and molded or otherwise affixed to the rearwardly or upwardly projecting sleeve-like extension 7 of a spring-tensioned tip 8 longitudinally slotted at the extreme end of the tip at 8^a to provide spaced jaws that are expanded by the lead as it is fed therethrough. This permits effective feeding of the lead, yet holds it rigid during writing.

Mounted within the upper extension 10 of the barrel 2, which also is preferably formed of a suitable plastic composition or the like, is a sleeve 40 11 suitably affixed at its lower end in the barrel and its upper end extending therebeyond to form a chamber A for spare or extra leads. The chamber is preferably closed by an eraser 12 and a cap 13 frictionally retained upon the sleeve 11, the cap being readily removable for access to the eraser and both being removable for reloading the pencil or for the insertion of additional leads.

Centrally mounted within the barrel 2 is a slotted tube 14 extending downwardly into the tip assembly and having an offset at one side thereof to provide longitudinally extending spaced flanges 15 forming a channel 15^a for receiving a flat feed key 16. As shown more clearly in Figs. 2, 7 and 8, the channel 15^a is closed by 55 an overlapping part 15^b from the upper end of the tube 14 to the base B of the lead magazine or chamber A and against which the lower end of the part 15^b abuts. This feed key is provided at one end with an extension or part 17 projecting into a convolution of a spiral slot 18 provided

or formed in a sleeve 19, and an enlarged part or extension 20 projecting through the slot and into the lead passage 21 in the sleeve for engaging or seating against the upper end of a lead 22. This feed key and tube 14 remain stationary or non-rotatable in the barrel, but, by affixing or securing the lower end of the sleeve 19 in the tip, this sleeve rotates or is turned with the tip and relative to the barrel 2 and tube 14, whereby turning of the tip in one direction advances the feed key 16 and it in turn advances the lead. Turning the tip in the opposite direction, retracts the feed key and permits pushing back of the lead.

When the key reaches the limit of its forward movement, as when the extension or part 17 engages against the shoulder or end 23 of the fixed tube 14, shown in dotted lines in Figure 1, further advance of the key is prevented. The tip is then turned in the opposite direction until the key reaches the position shown in Fig. 10, which is the limit of its rearward movement. In this extreme retracted position, the projecting end or part 20 leaves the spiral slot and leans or tilts to one side in the offset 25 as shown in Figure 6 to thereby uncover the lead passage 21. Upon removal of the cap 13 and eraser 12, leads removed from the storage space or other available leads are then dropped into the passage 21, and upon turning the tip to advance the key and lead, the extension or part 20 is automatically returned to its operative position in the spiral slot or groove, it being understood that the end or projection 17 remains in the spiral slot. To insure against removal of the key, a stop 26 is preferably provided to thereby prevent the key from being completely withdrawn from the barrel.

From the above description and the disclosure in the drawings, it will be readily apparent that the present invention comprehends a novel mechanical pencil of the rear loading type that is positive in operation, comprises a minimum number of operating parts, and contains a novel feed mechanism for actuating the lead.

Having thus disclosed the invention, I claim:

1. In a mechanical pencil, the combination of a barrel, a tip rotatably but non-removably mounted upon the barrel, a tube secured within the barrel and provided with a longitudinally extending offset, a lead-carrying sleeve rotatably mounted within the tube and provided with a spiral slot, means for connecting the sleeve to the tip, and a key carried within the offset and provided with spaced projections at its opposite ends projecting into the spiral slot whereby rotation of the tip relative to the barrel causes the key to move longitudinally in the slot, one of said projections extending through the slot and into the sleeve for thereat engaging the upper end of the lead and thereby advancing the lead in the sleeve.

2. In a mechanical pencil, the combination of a barrel, a non-removable tip rotatably mounted on the end of the barrel, a tube secured within the barrel, a lead-carrying sleeve rotatably mounted within the tube and secured to the tip, a spiral slot provided in the walls of the sleeve, and an elongated lead-feeding member carried within the tube and provided with spaced projections extending into the spiral slot with one of said projections extending through the slot to engage the upper end of and feed the lead through the sleeve.

3. In a mechanical pencil of the rear loading

type, a barrel, a tip rotatable with respect to the barrel, a lead-carrying sleeve provided with a spiral slot and connected to the tip, a hollow member encompassing the sleeve and secured to the barrel whereby the tip and sleeve may be rotated relative to the hollow member and barrel, a lead-feeding member carried in the hollow member and provided with spaced projections extending radially into the spiral slot with one of the projections adapted to engage the upper end of the lead carried in the sleeve for advancing the lead therethrough upon rotation of the tip in one direction, and when the tip is rotated in the other direction to retract the lead-feeding member to the limit of its rearward movement, the open end of the sleeve is uncovered to permit the insertion of additional lead.

4. In a mechanical pencil of the rear loading type, a barrel, a tip rotatable with respect to the barrel, a lead-carrying tubular member open at its lower end for discharge of lead and at its upper end for the insertion of additional lead and connected to the tip for rotation therewith, a spiral slot provided in said member, a hollow member encompassing the tubular member and secured in the barrel against rotation, an elongated lead-feeding key carried in the hollow member and retained therein against rotation, and spaced projections on said key extending into the spiral slot in such manner that upon rotation of the tip the tubular member advances and retracts the key, one of said projections extending through the slot and into the tubular member for engaging the upper end of the lead and advancing the lead when the tip is rotated in one direction.

5. In a mechanical pencil, a barrel, a tip non-removably but rotatably mounted on the end of the barrel, a hollow member secured in the barrel against rotation and provided with a channel extending for the full length of the member, a lead-feeding member slidably mounted in the channel, a tubular lead-carrying member rotatably mounted in the hollow member and secured to the tip for rotation therewith, a spiral slot in said tubular member, spaced projections on the lead-feeding member projecting into the slot with the upper of said projections extending into the tubular member for engaging the upper end of the lead carried therein, a stop provided at the lower end of the hollow member for interrupting advance of the lead-feeding member, and an offset at the upper end of the hollow member so positioned and arranged that as the lead-feeding member is fully retracted upon rotating the tip, the upper projection thereon leaves the slot and moves to one side to permit the insertion of additional lead.

6. In a mechanical pencil, means for feeding lead therethrough comprising a lead carrying member having a spiral slot, a tubular member encompassing the first mentioned member and provided with a longitudinally extending channel, and a feed key longitudinally movable in the channel and provided with projecting ends extending into the spiral slot with one end projecting therethrough for engaging and feeding lead through the pencil.

7. In a mechanical pencil, a lead-carrying sleeve having a spiral slot and open at its rear for the insertion of lead, a tubular member encompassing the sleeve and provided with a longitudinally extending groove, an elongated lead feeding member carried in the groove and having its spaced ends seating within the spiral slot

with the upper of said ends projecting through the slot and into the sleeve for feeding the lead therethrough.

8. In a mechanical pencil, a barrel, a tip rotatably but non-removably secured upon an end of the barrel, an elongated tubular member secured within the barrel and provided with a longitudinally extending groove, a spirally-slotted sleeve telescoped within the member and rotatable with the tip, and a feed key carried in the groove of said member and provided with projections seating within the spiral slot of the sleeve with one of the projections being of such length as to

extend through the slot and into the sleeve for engaging the upper end of the lead for advancing it through the sleeve.
